UNITED STATES PATENT OFFICE.

KING E. STOKER, OF STOCKTON, CALIFORNIA.

DIRECTION-SIGNAL FOR MOTOR-VEHICLES.

1,226,826.

Specification of Letters Patent. Patented May 22, 1917.

Application filed June 2, 1916. Serial No. 101,261.

To all whom it may concern:

Be it known that I, KING E. STOKER, a citizen of the United States, residing at Stockton, in the county of San Joaquin, 5 State of California, have invented certain new and useful Improvements in Direction-Signals for Motor-Vehicles; and I do declare the following to be a full, clear, and exact description of the same, reference being had to the accompanying drawings, and to the characters of reference marked thereon, which form a part of this application.

This invention relates to improvements in attachments for motor vehicles and particularly to signals therefor used to indicate the direction in which the vehicle is to turn and also when it is to be stopped thus avoiding collisions due to the fact that a machine following or approaching another machine 20 does not usually know what the other machine is liable to do.

In many places there is legislation requiring the extending of the hand in order to give the proper signal but this is often inconvenient and sometimes impossible and is 25 at best a very poor way of signaling.

My improved invention is designed to provide an automatic signal which can be thrown out merely by pressing an electric 30 button, one of said signals being placed on each side of the vehicle at any desirable point.

A further object of the invention is to produce a simple and inexpensive device and yet 35 one which will be exceedingly effective for the purposes for which it is designed.

These objects I accomplish by means of such structure and relative arrangement of the parts as will fully appear by a perusal of 40 the following specification and claim.

In the drawings similar characters of reference indicate corresponding parts in the several views.

Figure 1 is a front elevation of the vehicle showing my improved signal in position.

Fig. 2 is a sectional view of the improved signal.

Fig. 3 is a diagrammatic outline of the wiring plan showing the electric connections 50 of the signal.

Referring now more particularly to the characters of reference on the drawings, I first provide screws 1 arranged to be fastened at any desirable point on the vehicle,

which screws hold in place the cylindrical 55 casing 2 which is provided with a quarter round slot 3.

The casing 2 is provided with a central pin 4 on which is mounted the signal arm 5. This signal arm 5 on one side extends 60 through the slot 3 where it is provided with a signal member 6 which may be in the form of a hand, arrow or any other fanciful design found desirable. The other end of the arm 5 is provided with a semi-circular armature 65 core 7 which, when the signal 6 is in a vertical position, stands substantially as shown by dotted lines in Fig. 2.

A curved coil 8 is disposed within the casing 2 and when energized attracts the 70 armature 7 and draws the signal arm 5 to horizontal position so as to extend the signal 6 horizontally outward from the vehicle as shown by dotted lines in Fig. 1.

Within the signal 6 is a lamp 9 which is 75 wired to a switch 10 which switch is closed to connect the circuit through the lamp 9 when the horizontal position of the signal 6 is reached.

In practice I provide one of my improved 80 signal mechanisms on each side of the vehicle at some convenient point and electrically operate one or the other by means of a switch blade 11 which will make a circuit from the source of electrical energy 12 85 through one or the other of the signals. This circuit is particularly described as follows:

From the source of electrical energy 12 a wire 13 leads to the coil 8 and a wire 14 leads 90 from the coil to the point 15. From the other side of the source 12 a wire 15 leads to a switch blade 11. From the wire 13 a wire 13^a branches and connects with the other coil 8^a of the opposite signal while a wire 95 14^a leads from such coil 8^a back to the point 18. The moving of the switch blade 11 into contact with the points 15 or 18 will complete a circuit through either the coils 8 or 8^a respectively to throw up the signal on one 100 side of the vehicle or the other. Assuming that the signal 6 was the one thrown into operation this would throw the switch 10 to closed position which would complete a circuit from the source 12, through the wire 105 19, lamp 9, switch 10 and wire 20 back to the source 12. If the signal 6^a was the one thrown to horizontal position then a circuit

would be completed from the source 12, through the wire 21, lamp 9^a, switch 10^a, and wire 22 back to the source. Thus either the 5 lamp 9 or 9^a would be lighted according to whatever signal was thrown to horizontal position.

To drop the signal back to vertical position the switch blade 11 is moved to a neutral point between the contact points 16 and 10 18. This switch blade 11 may be either an ordinary switch blade or push button or any of the various forms used for making the necessary connections.

While I have herein designated a single 15 coil for use in connection with the device, still in practice it will be readily understood that I can use one or more of such coils as will be found most proper in order to fully operate the signal.

20 From the foregoing description it will readily be seen that I have produced such a device as substantially fulfills the objects of the invention as set forth herein.

While this specification sets forth in detail 25 the present and preferred construction of the device, still in practice such deviations from

such detail may be resorted to as do not form a departure from the spirit of the invention as defined by the appended claim.

Having thus described my invention what 30 I claim as new and useful and desire to secure by Letters Patent is:

A signal mechanism comprising an annular casing, a central transversely disposed pin within the casing, a signal lever turnable 35 on the pin, said lever projecting on each side of the pin, a curved armature on the inner end of the lever, a signal arm on the other end of said lever, the casing being provided with a quarter circular slot in its circumference 40 through which the signal arm projects, the ends of the slot acting as stops to limit the movement of the signal arm in either direction, a curved solenoid adapted when energized to act on said armature to move the 45 signal arm in one direction, such signal arm being adapted to drop in the opposite direction by gravity when the solenoid is de-energized, and means for energizing and de-energizing the solenoid.

50 In testimony whereof I affix my signature.
KING E. STOKER.
